ATTORNEY

UNITED STATES PATENT OFFICE

GEORGE M. MAGRUDER, OF BLACKVILLE, SOUTH CAROLINA

POLE OR MAST CONSTRUCTION

Application filed March 26, 1932. Serial No. 601,437.

This invention relates to a pole or mast construction adapted for use in supporting lamps, flags, sails, antennas, or any type of device wherein it is desirable at times to have access to the top of the pole without requiring climbing.

It has been proposed to provide a rigid base member for a flag pole, mast, or antenna pole so that when the pole requires painting or it is necessary to reach the extreme free end of the pole for any purpose whatever, it is necessary to hire someone particularly skilled in this art to climb the pole.

An object of the invention is the provision of a device in the form of a pole or mast adapted to be supported in a vertical position which is swingably supported adjacent its lower end and provided with a ballast so that the pole or mast may be released and swung to a horizontal position adjacent the support.

Another object of the invention is the provision of a pole or mast swingably mounted adjacent its lower end in a pair of arms supported by a base member with a ballast or weighted member suspended from the bottom of the pole and movable between the spaced arms, means being employed for securing the pole or mast or the weighted member against movement while retaining the member in a vertical position, the securing means being releasable to permit the pole or mast to be swung to a horizontal position.

A further object of the invention is the provision of a mast construction having a hollow member swingably mounted between a pair of arms forming a support, the hollow member being provided with a trap door for supplying the interior of said member with material which will act as a weight to counterbalance a pole projecting vertically from the hollow member, means being employed for releasably retaining the hollow member and pole in a substantially vertical position.

This invention will be best understood from a consideration of the following detailed description, in view of the accompanying drawings forming a part of the specification; nevertheless, it is to be understood that the invention is not confined to the disclosure, being

susceptible of such changes and modifications which shall define no material departure from the salient features of the invention as expressed in the appended claims.

In the drawings:

Figure 1 is a view in elevation, partly in section, of a mast constructed in accordance with the principles of my invention.

Figure 2 is a view in elevation taken at right angles to the view shown in Figure 1.

Figure 3 is a fragmentary horizontal section taken along the line 3—3 of Figure 1.

Figure 4 is a plan view of a modified form of the mast construction.

Figure 5 is a vertical section of the modified form.

Figure 6 is a view in elevation of the device shown in Figure 5 at right angles to said view, and

Figure 7 is a view in elevation of a base member and support applied to a gabled roof.

Referring more particularly to the drawings, 10 designates a base member which is secured in a substantial manner in the ground or top of a flat roof, as shown at 11. A sleeve 12 is threaded onto the base member 10 which is in the form of a pipe and a stem 13, formed integrally with a support 14, is threaded into the sleeve 12.

The support 14 includes a pair of curved arms 15 and 16 which are bowed outwardly and are provided with bearings 17 at their upper free ends.

A block 18 is provided with trunnions 19 carried by the bearings 17 on the arms 15 and 16.

A pipe 20 is located within a passage 21 formed centrally of the block 18. A collar 22 is threaded on the outer end of the pipe 21 and abuts the outer face of the block 18. A collar 23 is threaded on the inner end of the pipe 21 and abuts the inner face of a semi-spherical member 24. By means of the collars 22 and 23 and the sleeve 21, the semi-spherical member 24 is secured to the block 18.

A second semi-spherical member 25 has its inner edge resting within a flange 27 on the lower end of the semi-spherical member 24. The two members 24 and 25 form a hollow

casing which receives concrete, rock, crushed stone, or any suitable material which will act to counterbalance the length of a mast or pole which is carried by the casing, as shown at 28. The lower member 25 of the casing is provided with an opening 29 through which the materials are inserted. A door 30 is hinged at 31 to the semi-spherical member 25 and a latch 32 maintains the door 30 closed.

A pipe 35 is threaded into the sleeve 23 and extends axially of the casing generally designated by the numeral 36. The lower end of this pipe is threaded, as shown at 37, and passes through an opening in the bottom of the semi-spherical member 25. A nut 38 threaded onto the lower end of the pipe 35 maintains the semi-spherical member 25 in position.

The lower end of the pipe 35 is closed, as shown at 39, and is provided with an opening 40 through which projects a pin 41 having a head 42 which normally rests upon the closure 39 and prevents the pin from falling from the pipe 35. A pin 43 extends transversely of the pipe 35 adjacent the head 42 of the pin 41 and prevents the pin from moving too great a distance inwardly of the pipe.

A curved plate 50 is secured at 51 to the support 14 and is provided with an opening 52 to receive the pin 41 and lock the casing 36 against swinging movement.

A mast 53, which in this instance is shown as a tubular member, is threaded at 54 into the sleeve 22 and this tubular member extends to any desired height. The weight of the mast 53 is equal to the weight of the casing 36 together with the contents 28 so that the casing 36 acts as a ballast for the mast 53.

The support 10 may be varied so that it can be applied to any type of roof or projection on the roof or it may be mounted directly in the ground.

When the device is in position and the pin 41 engaged with the opening 52 in the plate 50, the mast 53 will be held in a vertical position.

If it be desired at any time to repair the mast, it is only necessary to remove the fastening means 51 from the support 14 so that the pin 41 will be released and the mast may then be moved to a horizontal position for any operations desired since the counterbalance 36 will permit ready lowering of the mast to such position.

All of the parts of the device may be made of metal which will stand the strains, thereby providing for a very compact construction.

Referring more particularly to Figs. 4 to 6, inclusive, it will be seen that a modified form of the invention is disclosed. In this case the arms 60 are curved at their lower end, as shown at 61, to provide a yoke which is formed integrally with a stem 62. The casing 63 is substantially cylindrical except the

bottom which is semi-spherical as shown at 64, to provide freedom of movement through the yoke 61. The upper end of the casing 63 is closed by a top 65 and this top is provided with a door 66 hinged at 67 to permit the insertion of the weighting material 68. A latch 69 maintains the door closed.

The cross bar 70 is secured at 71 to a pipe 72 passing axially and vertically through the casing 63. Trunnions 73 project diametrically from the casing 63 and are mounted in bearings 74 formed at the upper end of the arm 60. A pipe 72 forms the lower end of a mast 75 which projects beyond the top 65 a distance which will be determined by the use for which the mast is to be employed.

The lower end of the pipe 72 is provided with a pin 80 to prevent a locking pin 81 from moving inwardly on the pipe 72 when the mast 75 has been placed in a horizontal position. A head 82 on the pin rests upon a closure 83 at the lower end of the pipe 72 while the pin 81 is movable through an opening 84 in the closure. A nut 85 secures the lower end of the pipe 72 to the bottom 64 of the casing 63.

I claim:

1. A mast construction comprising a support, a mast having the lower end swingably mounted in the support, a weighted member carried by the mast below the mounting, a tubular member connected with the mast and extending through the weighted member and means for removably securing the tubular member to the support to prevent swinging movement of the mast.

2. A mast construction comprising a base member, a support including a pair of spaced arms rising from the base member, a weighted member, means for swingably supporting the weighted member on the free ends of the arms, a mast rising from the weighted member, means for securing the mast to said weighted member, a movable pin projecting from the lower end of the weighted member, the base member having an opening to receive the pin and hold the weighted member and mast in a vertical position.

3. A mast construction comprising a base member, a support rising from the base member, a hollow metal casing swingably mounted on the support, weighting materials in the casing, a door closing an opening in the walls of the casing, the opening providing means for supplying the interior of the casing with the weighting materials, a mast rising from the casing and adapted to be held in a vertical position by the weighted casing, and means for releasably retaining the weighted casing in position.

4. A mast construction comprising a base member, a support including a pair of spaced arms rising from the base member and provided with bearings on the free ends thereof, an elongated casing having trunnions mount-

ed in the bearings, a slidable locking pin projecting from the lower end of the casing, a plate removably secured to the support adjacent the bottom of the casing and provided with a passage to receive the locking pin and retain the casing against swinging movement, a mast connected to the casing and projecting upwardly therefrom, said casing having weighting materials therein to ballast the mast so that when the plate is removed the mast may be readily lowered to a substantially horizontal position.

5. A mast construction comprising a base member, a support having bearings, a block swingably supported in the bearings, a weighted casing secured in suspended relation to the block, a pipe passing vertically and centrally of the casing and secured to the block and casing, a mast rising from and secured to the upper end of the pipe, and means for releasably connecting the lower end of the pipe to the support for maintaining the mast normally in a vertical position.

6. A mast construction comprising a base member, a support having bearings, a block swingably supported in the bearings, a weighted casing secured in suspended relation to the block, a pipe passing vertically and centrally of the casing and secured to the block and casing, a mast rising from and secured to the upper end of the pipe, a pin slidably mounted in the lower end of the pipe and normally projecting therefrom, the support carrying a passage to receive the pin and retain the casing and mast in a substantially vertical position.

GEO. M. MAGRUDER.
